UNITED STATES PATENT OFFICE.

WILLIAM RABISILBER, OF HOBOKEN, NEW JERSEY, ASSIGNOR TO HIGH EFFICIENCY MOTOR CORPORATION, OF BROOKLYN, NEW YORK, A CORPORATION OF NEW YORK.

INTERNAL-COMBUSTION ENGINE.

1,262,952.

Specification of Letters Patent. Patented Apr. 16, 1918.

Application filed February 15, 1917. Serial No. 142,736.

To all whom it may concern:

Be it known that I, WILLIAM RABISILBER, a subject of the German Emperor, residing at Hoboken, in the county of Hudson and State of New Jersey, have invented certain new and useful improvements in Internal-Combustion Engines, of which the following is a specification.

My invention relates to internal combustion engines and more particularly to engines that can be operated with heavy oils, such as kerosene, fuel oil or crude oil, without the use of complicated mechanism, such for instance as employed in the construction 15 of the Diesel engine.

In the known type of internal combustion engine, the liquid fuel is supplied to the engine cylinder either direct by the use of injection pumps, or by means of highly compressed air. In the Diesel engine, highly compressed air, as is well known, is employed for injecting the liquid fuel into the combustion chamber, in which the air has been compressed up to the ignition point of 20 the fuel. A perfect combustion of even heavy oils is assured, but the regulating and controlling mechanism is so complicated, that it has failed in small-type high speed engines. Moreover, as is well known, in 25 Diesel engines very high pressures of from 600 to 1000 lbs. per square foot are required to insure a perfect vaporization and combustion of the fuel. Consequently, the weight of the engine becomes very great, too 30 great to enable the engine to be used on motor driven vehicles, such as automobiles.

In engines, on the other hand, where the liquid fuel is directly injected by small pressure pumps, without the use of the air, 35 the combustion is poor and imperfect, as a result of which the walls of the engine cylinder will be covered with deposits of soot. Moreover, in this latter case it is impossible to exactly control the small amount of liquid 40 fuel to be injected into the combustion chamber at each power stroke of the piston.

These difficulties are overcome by my invention, as the liquid fuel before being injected is first gasified by the heat generated 45 in the combustion chamber, and is then as a hot gas forced into the combustion chamber at the end of the compression stroke of the piston by a positively operated pump. As the fuel is thus injected into the engine 50 cylinder in the form of a highly heated gas,

the high pressures used in the Diesel engine to insure perfect combustion are unnecessary, whereas by throttling the gaseous fuel, during the suction stroke of the injection pump the amount of fuel to be forced into 60 the combustion chamber can be easily controlled.

The principle underlying my invention can be embodied in a slow running stationary engine, as well as in a high speed motor, 65 such as used on automobiles, flying machines, and in marine engines.

In the drawing in which my invention is shown embodied in a 4-cylinder, 4-cycle engine, Figure 1 is a plan view of the engine, 70 the cylinder head being shown partly removed; Fig. 2 is an irregular cross-section along A—B—C—D in Fig. 1; Fig. 3 shows a portion of the cylinder head seen from below; Figs. 4 and 5 are sectional views 75 showing details, the sections being respectively along lines E—F and G—H in Fig. 1.

The construction as shown is that of the regular T-head type of motor, in which the inlet and outlet valves are respectively arranged on opposite sides of the engine cylinders and in addition to which are provided the gas pumps on the exhaust side and the air pumps on the inlet side of the engine. A brief description of the principal parts 80 of the engine here follows:

1 is the engine cylinder containing the reciprocating piston 2, which through a connecting rod 3 operates the crank-shaft 4. Through the gear wheels 5, 5', 6 (shown in 90 broken lines in Fig. 2) the cam-shafts 7 and 8 are driven from the crank-shaft 4. The cam-shaft 7 controls the inlet valves 9 arranged on the right-hand side of the engine (see Fig. 2), while the cam-shaft 8 controls 95 the outlet valves 10 arranged on the left-hand side of the engine (Figs. 1 and 4). The cam-shafts 7 and 8 are also constructed as crank-shafts (Fig. 2), the cam-shaft 8 through connecting rod 11 operating the 100 plunger 12 of the fuel-injection pump 15, whereas the cam-shaft 7 through connecting rod 13 (see Fig. 5) operates the plunger 14 of the air pump 18.

The fuel injection pump 15 has an inlet 105 valve 16 and an outlet valve 17 (Fig. 2). In a similar manner, the air pump 18 on the opposite side of the engine cylinder cooperates with an inlet or suction valve 19 and an outlet valve 20 (Fig. 5).

As shown in Fig. 1, the liquid fuel container 21 is connected by a conduit 22 with the exhaust manifold 23. The latter has two chambers, a lower chamber 24 for the exhaust of the hot products of combustion, and an upper chamber 25 into which the fuel supply conduit opens at 26 (Fig. 1). The upper chamber 25 is so constructed that a large surface of its walls is exposed to the heat of the hot products of combustion so that, as the liquid fuel flows through the upper chamber 25, it is quickly converted into a hot gas. Between the chamber 25 and the chamber 29, the latter containing the valve 16 above mentioned, communication is established through the two bores 46 and 28 clearly seen at the left in Fig. 2, a throttle 27 being interposed between these two bores. As the plunger 12 in the cylinder of the fuel injection pump 15 performs its outward stroke, the throttle 27 being in a position to permit free communication between the heated fuel chamber 25 and the chamber 29 of the inlet or suction valve 16, the gaseous fuel will lift the valve 16 from its seat and quickly flow through the bore 37 into the pump cylinder 15, the bore 37 connecting the latter with the chamber 29 as shown. Upon the inward stroke of the plunger 12, the gaseous fuel is then compressed and forced through the bore 30 and the bores 31, 32 into the combustion chamber 33 of the engine. The combustion chamber is produced by a recess 35 in the cylinder head 34 (Figs. 2 and 3). As the plunger 12 performs its inward stroke thereby putting the gasified fuel under pressure the outlet valve 17 which normally closes the bore 30, will momentarily be lifted from its seat against the pressure of its closing spring 47, to permit the gasified fuel to rush past it into the combustion chamber 33 through the said bores 31, 32 as stated.

The bore 32 for the admission of the gasified fuel joins with the bore 35 (Fig. 3) for the admission of compressed air in the bore 36 which latter terminates in the combustion chamber 33, as shown in Fig. 3.

On the right-hand side of the engine is arranged the inlet manifold 37 (Fig. 1), which is provided with a throttle valve 38 (Fig. 2). The latter, through the stem 39 (Fig. 1), link 40, connecting rod 41, link 42, (all shown in Fig. 2) and stem 43 is connected with the throttle 27 above mentioned. Therefore, as the stem 39 is turned in either direction, both throttles, 38 and 27, are simultaneously operated to either admit or shut off air for the working cylinder and gasified fuel for the gas pump.

The arrangement of the air pumps on the side of the engine where the inlet manifold is located, and of the valves coöperating therewith is identical with the arrangement

of the fuel injection pumps, as clearly seen in the drawing (Fig. 5) and therefore, will not need any further description, as the construction and operation will be entirely clear from the above description of the fuel injection pumps and their parts, except that the throttle valve shown on the left-hand side of Fig. 2 is omitted, the air being admitted directly through an open port.

The engine may be started by a supply of carbured air to the inlet manifold 37, so that for a brief period the engine will run as an ordinary gasoline engine. By the hot products of combustion the liquid fuel is quickly gasified in the heating chamber 25, and through a corresponding turn of the stem 39 the throttle valves 38 and 27 are opened so that corresponding amounts of air and gasified fuel respectively are admitted, the former to the engine and the latter to the gas pumps 15 which, upon the inward stroke of their plungers 12 force the gasified fuel into the combustion chambers of the various engine cylinders, where instantaneous and smokeless combustion occurs at the moment, the heated fuel comes into contact with the compressed air.

I claim as my invention:

1. An internal combustion engine comprising a working cylinder having a combustion chamber and provided with inlet and outlet ports, a piston in said working cylinder, means for converting liquid fuel into a gas by the heat generated in said combustion chamber, a pump for forcing the gasified fuel separate from the air into said combustion chamber at the completion of the compression stroke of the said piston, and a throttle valve for controlling the amount of gasified fuel to be forced by said pump into the combustion chamber.

2. An internal combustion engine comprising a working cylinder having a combustion chamber and provided with inlet and outlet ports, a piston in said working cylinder, a heating chamber for converting liquid fuel into a gas by the hot products of combustion, a pump for forcing the gasified fuel separate from the air into the combustion chamber at the completion of the compression stroke of the said piston, and means for controlling the amount of gasified fuel to be forced by said pump into the combustion chamber.

3. An internal combustion engine comprising a working cylinder having a combustion chamber and provided with inlet and outlet ports, a piston in said working cylinder, a heating chamber heated by the hot products of combustion for converting the liquid fuel into a gas, a pump for forcing the gasified fuel separate from the air into the combustion chamber at the completion of the compression stroke of the said piston, and a hand-controlled throttle valve

between said heating chamber and said pump.

4. An internal combustion engine comprising a working cylinder having a combustion chamber and provided with inlet and outlet ports, a piston in said working cylinder, a heating chamber formed in the exhaust manifold for converting the liquid fuel into a gas, a pump for forcing the gasified fuel separate from the air into the com-

bustion chamber at the completion of the compression stroke of the said piston, and a hand-controlled throttle valve between said heating chamber and said pump.

In testimony whereof I affix my signature 15 in the presence of two witnesses.

WILLIAM RABSILBER.
